UNITED STATES PATENT OFFICE.

HAROLD A. PETTERSON, OF TIENTSIN, CHINA.

DESIGN FOR A BANJO-UKULELE.

Application filed November 22, 1927. Serial No. 24,242. Term of patent 14 years.

To all whom it may concern:

Be it known that I, HAROLD A. PETTERSON, a citizen of the United States, residing in Tientsin, China, have invented a new, original, and ornamental Design for a Banjo-Ukulele, of which the following is a specification, reference being had to the accompanying drawing, forming part thereof.

Referring to the drawing:—

Figure 1 is a plan view,
Figure 2 is an end elevation, and
Figure 3 is a side elevation of a banjo-ukulele embodying my design.

I claim:

The ornamental design for a banjo-ukulele, as shown.

HAROLD A. PETTERSON.
